UNITED STATES PATENT OFFICE.

OTTO SPAHR, OF PHILADELPHIA, PENNSYLVANIA.

BOTTLE-CLOSURE.

1,156,562.

Specification of Letters Patent.

Patented Oct. 12, 1915.

Application filed December 19, 1914. Serial No. 878,020.

To all whom it may concern:

Be it known that I, OTTO SPAHR, a citizen of the United States, residing at Philadelphia, county of Philadelphia, and State of Pennsylvania, have invented a new and useful Improvement in Bottle-Closures, of which the following is a full, clear, and exact description, reference being had to the accompanying drawings, which form a part 10 of this specification.

Caps or closures for bottles, intended more especially for application to bottles of milk after the same have been delivered by the dealer to the housekeeper, and which operate 15 to seal the bottle when not in use but permit the milk to be poured from the bottle without removal of the closure, are known in the art; but the same are open to various objections, such as inadequately tight closure, difficulty of application and removal, 20 imperfect provision for proper outlet of the milk in pouring, expense of manufacture, etc. In an application filed by me August 15, 1914, Serial No. 856,937, I set forth an 25 improved closure in which these objections are substantially overcome.

The object of the present invention is to improve the closure set forth in said application, and particularly to insure the entire 30 absence of leakage in pouring, to render certain, after pouring, the return of every drop of liquid in the spout to the interior of the bottle, to prevent breakage of the cap adjacent to the spout as a result of repeated 35 use, and to strengthen the cap so that it will not suffer distortion as a result of careless handling.

A preferred embodiment of the invention is shown in the accompanying drawings, in 40 which—

Figure 1 is a plan view of a cap embodying my invention; Fig. 2 is a vertical sectional view of the cap applied to a bottle; Fig. 3 is a view similar to Fig. 2 showing 45 the bottle tilted into position to pour the contained liquid; Fig. 4 is a plan view of the blank for the cap of Figs. 1, 2 and 3; Fig. 5 is a plan view of a modified form of blank.

From a flat piece of metal is cut a blank 50 disk *a* (see Fig. 4) of circular contour except for the provision of a projection *b* to form the spout and projections *c*, *c* and *d* to form the holding flanges, both hereinafter described. The piece is orificed at *e* and is 55 cut to form notches *f* extending beyond the outer corners of orifice *e*. The laterally

extending projection *b* is then bent at the corners and deflected somewhat upwardly to form a spout. Projections *c*, *c* and *d* are then bent downward and curved to form 60 holding flanges. Between the flanges the metal of the disk adjacent to the rim is bent downward to form a reinforcing flange *g*. Between notches *f* the metal of the spout portion *b* is bent down to form a lip *h*, 65 which acts as an inner extension of the spout and as an outer wall for the pouring orifice *e*.

Immediately back of the pouring orifice *e* the disk *a* is cut away to form a slot *i*. This 70 slot is preferably between the rear edge of the orifice *e* and the center of the disk and extends at a right angle to that radius of the disk which intersects the center line of the spout. A gate *k* is provided of sufficient area to cover orifice *e*. The gate *k* has a flange *m* which extends through slot *i*. The flange is provided with a counterweight *n*.

It will be observed that the dimension of 80 the spout *b* measuring circumferentially of the disk is substantially greater than that dimension of the spout measuring radially beyond the disk. It will also be observed that the length of the pouring orifice after 85 the lip has been bent down as in Fig. 1 (measuring at right angles to that radius of the disk which intersects the center line of the spout) is of about the length of the spout. The ends of the pouring orifice are 90 therefore opposite points on the edge of the disk substantially beyond the spout. By this construction it is insured that after the pouring operation and when the bottle *x* is moved into an upright position, all the 95 milk or other liquid remaining in the spout will flow back into the bottle. Further, owing to the direction of inclination of the disk in pouring, all the milk emerging from the orifice will necessarily flow to the spout 100 and none of it will tend to flow over the edge of the disk beyond the spout.

It is important, in pouring, that all the 105 milk shall flow out orifice *e* and that none of it shall escape between the under surface of the disk and the neck of the bottle. This is insured by the provision of lip *h*; but to insure that the lip will be maintained tight against the inside of the bottle neck there are provided two holding flanges *c*, *c*, adjacent to spout *b* and only one holding flange *d* along the remainder of the disk. Thus it 110

is insured that the edge of the disk provided with the spout shall be held down against the bottle neck with greater pressure than the opposite edge of the spout is held down, 5 whereby the lip *h* is held tightly against the inside of the bottle neck. This result is further insured by reason of the shape of the flanges which are curved on a smaller radius than the outer wall of the rim of the bottle 10 neck. The same result may be secured by constructing the closure as in Fig. 5, in which, for a single flange *d*, are substituted three flanges *o*, *o*, *o*, each substantially narrower, and therefore weaker, than either of 15 the flanges *c*.

The shape of the flanges gives to them the elasticity required to enable the cap to be readily applied and removed, while the engagement between the flanges and the bottle 20 neck is such as to hold the cap tightly down on top of the bottle and securely in position.

The narrow reinforcing flange *g* is not intended to engage and ordinarily does not engage, the rim of the bottle neck, but the 25 provision of this flange reinforces the disk so that it will not become distorted as a result of careless handling.

Having now fully described my invention, what I claim and desire to protect by Letters Patent is:

1. A bottle cap or closure comprising a disk, a laterally extending upwardly inclined spout extending along the edge of the disk for a distance substantially greater 35 than the width of the spout measured radially of the disk, the disk back of said spout being cut away to form a pouring orifice opposite ends of which extend substantially beyond radii of the disk between which the 40 entire spout is contained, and a movable gate for said orifice.

2. A bottle cap or closure comprising a disk, a laterally extending upwardly inclined spout extending along the edge of the disk for a distance substantially greater 45 than the width of the spout measured radially of the disk, the disk back of said spout being cut away to form a pouring orifice whose length, measured at a right angle to 50 that radius of the disk extending along the center of the spout, is substantially greater than its width measured along said radius, and whose opposite ends extend substan-

tially beyond radii of the disk between which the entire spout is contained, and a 55 movable gate for said orifice.

3. A bottle cap or closure comprising a disk, a laterally extending upwardly inclined spout projecting from the disk, there being a pouring orifice in the disk back of 60 the spout, a downwardly bent lip along the front wall of said orifice, two downwardly extending curved flanges beyond and adjacent to opposite ends of the spout and located opposite the ends of said orifice, the 65 semi-circumference of the disk opposite the spout having a flanged portion of less strength than the first mentioned flanges, whereby when said disk is applied to a bottle neck with the flanged portion thereof 70 engaging the outer wall thereof, the lip will be held firmly against the inner wall of the bottle neck.

4. A bottle cap or closure comprising a disk, there being a pouring orifice in the disk 75 and a slot adjacent to the pouring orifice, a spout projecting from the disk in front of the pouring orifice, a swinging gate for said orifice, and a weighted flange on the gate extending through the slot and adapted to 80 effect the opening of the gate when the bottle is tilted toward a horizontal position.

5. A bottle cap or closure comprising a disk, a laterally extending upwardly inclined spout whose length, measured along 85 the edge of the disk, is substantially greater than its width measured radially of the disk, the disk between its center and the spout being cut away to form a pouring orifice whose length, measured at a right angle 90 to that radius of the disk extending along the center of the spout, is substantially greater than its width measured along said radius and approximates the length of the spout, and a downwardly bent lip along the 95 front wall of said orifice adapted for engagement with the inside of the rim of the bottle neck.

In testimony of which invention, I have hereunto set my hand, at Philadelphia, on 100 this 18th day of December, 1914.

OTTO SPAHR.
